ARTICLE HANDLING DEVICE

Charles McNeillie, Midland, Pa.

Application May 27, 1937, Serial No. 145,124

4 Claims. (Cl. 294—67)

The present invention relates generally to hoisting and transporting devices and more particularly to billet carriers having a load releasing arrangement associated therewith by means of which various articles may be lifted, moved and dumped from the carrier in a simple convenient manner.

More specifically the device comprises a fork-like member formed in such a manner that a load-carrying portion may be moved under a group or stack of elongated objects such as steel billets, railway ties and the like. The fork-like carrier is further shaped in such a manner that when the upper end thereof is supported from a crane, or derrick, the load-carrying portion will be in an approximate horizontal position and thus permit convenient movement of the device under the stack from which the material may be lifted and moved.

An object of the present invention is to provide such a load-moving device with simple means which automatically responds to the movement of the crane to dump the material from the device.

Another object of the invention is to provide, a fork-like device which is adapted to have a load-carrying portion normally supported in a horizontal manner, with means for automatically tilting the device.

A still further object of the invention resides in the provision of a self-contained load-carrying device which may be moved under the material to be transported whereby the same may be hoisted by a crane, transported and dumped therefrom simply by the manner in which the crane is operated.

Other and further features and objects of the invention will be more apparent to those skilled in the art upon a consideration of the accompanying drawings and the following description wherein an exemplary embodiment of the invention is disclosed.

In the drawings:

Figure 1 is a general view, in side elevation, of a load-carrier and dumper constructed in accordance with the invention.

Figure 2 is a plan view of an end of the device shown in Figure 1.

Figure 3 is another view in end elevation illustrating the manner by which the device is tilted to dump the load therefrom.

Referring to the drawings there is shown in Figure 1 a group or stack of steel billets, railroad ties or like objects 10 positioned upon a plurality of spaced joists 11 so that the material to be

lifted and moved is slightly elevated with respect to any flat supporting surface 12.

In carrying out the invention a carrier which may be regarded as being of a fork-like construction is shown generally at 15 in the various figures 5 and is represented as comprising a plurality of angular bars 16 of any preferred cross sectional shape including a similar number of normally horizontal load-carrying arms 17.

The upper ends of the angular bars 16 are secured to a transverse connecting bar 18 which constitutes the top of the element. The load-carrying arms 17 in actual construction of the device may be integrally formed from a continuation of the bar 16, as for example, by bending 15 or forging the same into the form illustrated in Figures 2 and 3. The load-carrying arms 17 and the angular bars 16 may be rigidly held in a spaced relation by a pair of cross braces 19 which extend respectively from each upper corner of the 20 element downwardly to the opposite angular bars 16. Further bracing may be provided by a transverse member 20 which is secured to the bars 16 in any well known manner.

The fork-like carrier is intended to be lifted 25 and moved about by any suitable hoisting device such as a derrick, crane or like device and the top connecting member 18 is therefore equipped for this purpose with suitable suspension means.

The hoisting and transporting device may comprise a boom or other suitable device (not shown) from which depends a cable 21 carrying a hook 22 at the end thereof. Suspended from the hook 22 and an appropriate hook-engaging ring 23 is a pair of chains 24 and 26 which extend respectively to and are adapted to be securely engaged in the eyelets 27 and 28 carried by each end of the transverse member 18.

The fork-like carrier when suspended in such a manner and viewed from the end as shown in 40 Figure 2 has a general appearance of being substantially L-shaped. The load-carrying arms 17 may therefore be moved by the crane under a group of elongated objects stacked in a manner as hereinabove described in connection with 45 Figure 1. Upward movement of the crane cable and hook 22 will cause the arms to engage the billets or the like. The bars 16 or the upper portion of the generally L-shaped carrier converges 50 slightly towards the load-carrying arms so that when the device is thus loaded the center of gravity of the load will not cause the substantially horizontal position of the arms 17 to be altered. With the device loaded in such a convenient man- 55

ner the material may be hoisted and moved to the desired point for unloading.

The invention includes simple means for automatically tilting the fork-like carrier so that the material loaded thereon may be discharged therefrom by simple manipulation of the lifting hook 22 carried by the crane. For the purpose of carrying out this desirable function each bar 16 is provided with a rearwardly extending projection 5 or hook 29 positioned intermediate of the connecting member 18 and the lowermost portion 10 or hook 29 positioned intermediate of the connecting member 18 and the lowermost portion 15 of the device and preferably at the points where the bars 16 converge slightly towards the center of the load-carrying elements. In other words, if the lifting force of the crane is also applied 20 at these points tilting of the carrier will be effected. A rod 31 extending across the back of the bars 16 is adapted to be suspended by means of a pair of chains 32 and 33 and provide one 25 part of apparatus for dividing the lifting force as hereinabove described. The chains are secured respectively to the links or rings 34 and 36 interposed in the carrier supporting chains 24 and 26 and the rod suspending chains are of such length 30 that when the carrier is totally supported by the chains 24 and 26 the transversely extending rod 31 floats immediately below the connecting member 18. Suitable means may be provided for preventing lateral movement of the chains 32 and 33 with respect to the rod such as collars 37 which 35 are secured to the rod 31 in a spaced relation to form fastening devices for the lower links of the tilting chains.

A skid 38 is associated with each projection 35 or hook 29 so that a relatively smooth surface is provided on the rear face of each of the angular bars 16. It will be apparent, however, that rear faces of the bars 16 may be shaped with integrally formed projections to provide substantially 40 straight sloping surfaces from the normal position of the rod 31 to the tips of the hooks 29.

In the operation of such a carrier the arms 17 may be moved under a group of elongated objects 10 which have been stacked in a manner as 45 illustrated in Figure 1. In other words when the carrier 15 is supported for upward and horizontal movement by means of the crane hook 22 and the chains 24 and 26 the arms will be in a normal position or substantially horizontal so 50 that they may be conveniently moved under the material to be transported. After the arms 17 are in a position beneath the elongated objects 10 upward movement of the crane hook will cause the load-carrying arms to engage the material 55 and carry the same upwardly. The angular bars 16 being shaped as hereinabove described permit the arms 17 to remain in an approximately horizontal position, that is to say, the slight converging shape of the arms when suspended by the crane and the cross-connecting member 18 is such 60 that the chains 24 and 26 are in alignment with the center of gravity of the load and no tilting of the normally horizontal arms 17 takes place. The load may be thus lifted and transferred to 65 the desired destination by movement of the crane.

When the loaded carrier arrives at a point immediately above the new location the material carried thereby may be conveniently dumped by 70 simple manipulation of the crane. In other words, by lowering the carrier to a position where the arms 17 rest on a firm support further downward movement of the hook 22 will permit the chains 24 and 26 to sag. The chains 32 and 33 will therefore allow the rod 31 to slide down the 75 rear faces of the bars 16 and over the tips of

the projections 29. The slope of the rear faces of the bars 16 and the direction of the projections 29 are such that the weight of the rod 31 causes the same to fall over the ends of the hooks. With the rod 31 in the position just described upward movement of the crane will move the ends of the rod into engagement with the hooks 29. Further upward movement of the lifting means will tilt the carrier in a manner as illustrated in Figure 3 whereby the arms 17 then 10 slope to permit the elongated objects 10 to slide therefrom.

From the foregoing it will be apparent that the invention provides a carrier arrangement which is adapted to be lifted, moved and tilted 15 by the simple manipulation of a crane or derrick having but one load-carrying hook.

The ends of the rod 31 may be readily disengaged from the projections 29 to permit the arms 17 to again assume a horizontal position by 20 lowering the carrier to the ground after the load has been dumped. When the device is thus resting on a firm support further downward movement of the hook 22 will permit the chains 24 and 26 to again sag, thus allowing the rod 31 25 to move downwardly. After the ends of the rod pass the tips of the hooks 29 horizontal movement of the crane hook towards the back of the device will cause the rod to escape the hooks 29 when the carrier will again be supported solely 30 by the chains 24 and 26 on an upward movement of the crane and thus be ready for movement under another load of billets or the like.

Although a preferred embodiment of the invention has been described, it will be apparent 35 that modifications may be made by those skilled in the art. Such modifications may be made without departing from the spirit and scope of the invention as set forth in the appended claims.

I claim:

1. An article handling device comprising, a 40 fork-like carrier element consisting of load-carrying arms and bars extending angularly therefrom to provide a top for the carrier, flexible suspension means connected to the top of 45 said element adapted to normally support said load-carrying arms in a horizontal position, flexible tilting means connected to said flexible suspension means, and means carried by said flexible tilting means normally hanging free along 50 said bars adapted to engage said bars when said suspension means is permitted to sag whereby the carrier is tilted when said suspension means again supports the device.

2. A device of the class described comprising, 55 a fork-like carrier element consisting of load-carrying arms and bars extending angularly therefrom to provide a top for the carrier, a second pair of chains connected to the top of said element adapted to normally support said load- 60 carrying arms in a horizontal position, a second pair of chains, one of which being connected to each of said first mentioned chains, means carried by said second mentioned chains adapted to engage said bars when said first mentioned 65 chains are permitted to sag whereby the carrier is tilted when said first mentioned chains again support the device.

3. A device of the class described comprising, 70 a fork-like carrier element consisting of load-carrying arms and bars extending angularly therefrom to provide a top for the carrier, a pair of chains connected to the top of said element adapted to normally support said load-carrying arms in a horizontal position, a second 75

pair of chains, one of which being connected to each of said first mentioned chains, hooks projecting from said angular bars, means carried by said second mentioned chains adapted to engage said hooks when said first mentioned chains are permitted to sag whereby the carrier is tilted when said first mentioned chains again support the device.

4. A device of the class described comprising, a fork-like carrier element consisting of load-carrying arms and bars extending angularly therefrom to provide a top for the carrier, a pair

of chains connected to the top of said element adapted to normally support said load-carrying arms in a horizontal position, a second pair of chains, one of which being connected to each of said first mentioned chains, hooks projecting from said angular bars, a rod carried by said second mentioned chains adapted to engage said hooks when said first mentioned chains are permitted to sag whereby the carrier is tilted when said first mentioned chains again support the device. 5

CHARLES McNEILLIE.
